UNITED STATES PATENT OFFICE.

MIERLEY T. MCKEE, OF BELLE VALLEY, OHIO.

WELL-BORING DRILL.

1,075,843.

Specification of Letters Patent.

Patented Oct. 14, 1913.

Application filed May 23, 1912, Serial No. 699,340. Renewed January 20, 1913. Serial No. 743,304.

To all whom it may concern:

Be it known that I, MIERLEY T. MCKEE, a citizen of the United States, residing at Belle Valley, in the county of Noble and State of Ohio, have invented certain new and useful Improvements in Well-Boring Drills; and I do hereby declare the following to be a full, clear, and exact description of the invention, such as will enable others skilled in the art to which it appertains to make and use the same.

The present invention relates to drills for boring oil and similar wells, and has for its purpose to provide a tool for drilling a hole, having means associated therewith for enlarging the same progressively with the drilling operation; wherein said means is caused to automatically assume its functional position through the drilling operation of the tool, and to assume an inoperative position through the withdrawal of said tool.

The invention has for its further purpose to produce a tool of the character in question having the minimum number of parts of durable construction, which are assembled in the manner best suited to give prolonged and efficient use.

With these and other objects in view the invention consists in the novel details of construction and combinations of parts more fully hereinafter disclosed and particularly pointed out in the claim.

Referring to the accompanying drawings forming a part of this specification in which like numerals designate like parts in all the views:—Figure 1 is a central, vertical, sectional view of a well casing showing the drill and associated parts in front elevation; Fig. 2 is a front elevational, and partly sectional, view of the drill and lower end of the casing; Fig. 3 is a central, sectional view of the parts shown in Fig. 2, and taken at right angles thereto; and, Fig. 4 is a transverse sectional view of Fig. 3 taken on the line 4—4 thereof.

Referring to the construction in detail, the same consists of a bit 1 constructed of the usual material, and having the opposed faces 2 and 3 thereof downwardly and relatively inclined and terminating with a straight cutting edge 4. The head 5 of the bit is provided with an internally screw-threaded collar 6, which is detachably connected with the lower end of the shaft 7, as illustrated in Figs. 1 and 2. Said shaft

7 consists of a plurality of pipe sections suitably coupled together by collars 8, as shown.

The inclined faces 2 and 3 of the bit are each provided with a groove or channel 9 of dove-tailed cross section, and which have slidably mounted therein the dove-tailed heads 10 of the reaming bits or blocks 11. There are two of said reaming bits or blocks 11, i. e., one slidably mounted on each inclined face (2 or 3), and said members have for their purpose to enlarge the hole which is made by the cutting edge 4 progressively as the bit 1 works downwardly. The purpose for thus enlarging the hole is to permit of the following of the shoe 12 of the well casing 13, as will be understood. By reason of the inclined sides 2 and 3, said reaming bits 11 will be caused to work upwardly as the drilling bit 1 is forced downwardly, and for the same reason said bits will slide downwardly, or contract with respect to the bit, thus permitting of the bit 1 being readily withdrawn from the well casing 13.

To permit of inserting and removing the reaming bits 11 from the slots 9, the bit 1 is provided with a pair of blocks 14 located at the lower end of each of said slots 9. Said blocks or members 14 are of beveled edge construction (see Fig. 2) whereby to have a secure engagement therefor, and as a further fastening means each of the blocks is provided with a pin 15 which passes therethrough and into the body of the bit 1. With this construction it will be readily seen that the dove-tailed heads 10 of the reaming bits 11 may be inserted and removed from the slots 9 through the removal of the blocks 14.

The bit 1 is provided with a central channel 16 communicating at its upper end with the pipe shaft 7, and at its lower end said channel 16 communicates with a pair of downwardly disposed channels 17. The channels 16 and 17 are adapted to receive from the pipe 7 a flow of water mixed with loam and clay, which is forced through the pipe 7 from above in the usual manner. After issuing through the branch channels 17, said flow is forced upwardly between the bit and well casing to the surface, as in the ordinary well drilling. A hand turning wheel 18 is mounted on the shaft 7 for the purpose of turning the drilling bit 1.

It is obvious that those skilled in the art

may vary the details of construction and arrangement of parts without departing from the spirit of my invention, and therefore I do not wish to be limited to such features except as may be required by the claim.

What I claim is:—

In a well boring drill, the combination of a bit having opposed inclined faces, and 10 provided with a straight cutting edge, said inclined faces having formed therein slots of dove-tail cross section and terminating at their lower ends adjacent the cutting edge of the bit; a pair of reaming bits having integrally formed dove-tailed heads slidably mounted in said slots; said pair of reaming bits when at the lower ends of said slots 15 permitting of insertion and removal of the

first named bit and the reaming bits through the well casing; a pair of blocks having 20 beveled edges secured to the bit adjacent the lower terminating end of each slot permitting of insertion and removal of said reaming bits; and a pipe secured at one end to the head of the bit, said bit having a 25 central channel communicating at one end with said pipe and having opposed distributing ports at the other end thereof, substantially as described.

In testimony whereof, I affix my signature, in presence of two witnesses.

MIERLEY T. MCKEE.
